UNITED STATES PATENT OFFICE.

WILLIAM F. CONRAN, OF BROOKLYN, NEW YORK.

FITTING FOR STAND-PIPE SYSTEMS.

1,269,908.

Specification of Letters Patent. Patented June 18, 1918.

Original application filed March 26, 1917, Serial No. 157,558. Divided and this application filed October 10, 1917. Serial No. 195,731.

To all whom it may concern:

Be it known that I, WILLIAM F. CONRAN, a citizen of the United States of America, residing in the borough of Brooklyn of the 5 city of New York, in the county of Kings and State of New York, have invented a certain new and useful Improvement in Fit-tings for Stand-Pipe Systems, of which the following is a specification.

- 10 This application is a division of my application filed March 26, 1917, Serial Num-ber 157,558, and patented January 8, 1918, Patent No. 1,253,005, the invention relating to fire extinguishing systems employing a 15 main water supply line or pipe having a num-ber of outlets or branches at various points controlled by hydraulically operated valves which in turn are controlled from distant points or from a common operating sta-20 tion by hand operated control valves; and relating more particularly to a system of movable stand-pipes for buildings such as described in Letters Patent of the United States No. 816,152, granted to me March 27, 25 1906, but wherein the control pipes leading from the control valves to the hydraulically operated valves are carried within the main water supply pipe or movable stand-pipe, and the present invention relates to the 30 stand-pipe fitting through which the control-pipes project for connection to the hand operated control valves carried thereby, and which fitting is herein referred to as the control-fitting.
- 35 As described in my said application and patent, the outlets from the water supply or stand-pipe are controlled from an op-erating station or chamber, and the control-fitting is placed in the pipe-line at that 40 point. This fitting may be of any suitable shape circumferentially, but I prefer to have the body portion cylindrical in form, tapering toward the ends, and provided with flanges of large diameter. Each flange is 45 provided with two sets of holes, one set for the usual bolts for coupling pipe flanges, and the second set for the pins of a span-ner-wrench or turning bar. The body of the fitting is provided with bosses or pro-50 jections arranged in two rows extending entirely or partly around the body. Each boss of the upper row is in vertical aline-55 ment with a boss of the lower row, the two alined bosses forming a pair for each con-trol-pipe used in connection with the fit-
- ting. Both sets of bosses preferably project through the wall of the fitting at an angle of 45° , the upper row projecting upward on the inside and downward on the outside, and the lower row projecting in the oppo-60 site direction. The external diameter of the bosses will be such as to permit them to be bored through and have an internal bore large enough to receive the control-pipes with a surrounding packing material 65 and packing rings. At the central part of the body is a hand-hole with a suitable cap or cover-plate closed water-tight with a packing material and bolts. The size of the fitting will vary, of course, according to the 70 size of piping with which it is employed, and the diameter of the body will vary ac-cording to the number of control-pipes em-ployed, and consequently according to the 75 number of outlet-bosses to be provided.
- 75 My invention is illustrated in the accom-panying drawings, in which Figure 1 is an elevation of the fitting with attached con-trol-valves; Fig. 2 a central vertical section, 80 and Fig. 3 a central horizontal section.
- 80 Referring to the drawings, 1 is the cylindri-cal body of the fitting tapering toward the ends and terminating in stepped flanges 2 of large diameter. The thicker parts of these flanges are provided with bolt-holes 85 3 which register with bolt-holes in the usual pipe flanges shown in dotted lines, see Fig. 2. The part of flange 2 which projects be-yond the pipe flange has a series of holes 4 with which the pins on spanner-wrench or 90 turning-bar 5 (Fig. 1) engage to rotate the stand-pipe. The body part of the fitting has a hand-hole 6 which is covered by plate 7 secured by bolts 8, a layer of packing or 95 sealing material being in practice placed be-tween the flange of the hand-hole and plate to make a water-tight joint. In casting the fitting it is provided with two semi-circular rows of bosses 9 on the side opposite the 100 hand-hole, although if desired, the bosses may extend farther around the body or en-tirely around it. These bosses are prefer-ably set at an angle of 45° and extend through the wall of the fitting and are oval-shaped in cross-section at the exterior end 105 as shown in Fig. 3. Holes 10 are drilled through the bosses to receive control-pipes 11, the holes being of larger diameter than the pipes to afford space for packing ma-terial and packing rings 12 and 13; the 110

former being screwed into the boss from the inside, and the latter having an oval flange and forced against the packing material by screws 14. As shown the control-pipes 11 (only one being shown in Fig. 2) pass downward through the upper bosses 9 and are connected to control-valves 15. To the inlet side of each valve is attached a short section of pipe 11^a which passes through similar packing rings 12 and 13 and packing material in the lower boss 9, and to this pipe is attached a strainer 16. As shown in Fig. 2, the control-pipe and valve are for controlling a valve located above the fitting, but for a valve located below the fitting, the direction of pipes 11 and 11^a will be reversed, that is, pipe 11 will project downward through lower boss 9 and pipe 11^a will project upward through upper boss 9.

20 It will be observed that with my improved fitting the control-pipes may be readily carried within the main water supply or stand-pipe, thus protecting them from damage or disarrangement; that the control-valves may be readily carried by the fitting, and that the supply pipe, control-pipes and valves may be readily rotated or moved vertically as explained in my application above referred to.

30 What I claim is:

1. As a new article of manufacture, a fitting for stand-pipes, comprising a cylindrical body portion of large diameter and tapering at the ends to pipe size and arranged for attachment to pipe sections, a series of bosses on the body portion adapted to be bored and arranged to form stuffing-boxes, and a hand-hole and covering plate, substantially as set forth.
- 40 2. As a new article of manufacture, a fitting for stand-pipes, comprising a cylindrical body portion of large diameter and tapering at the ends to pipe size and having a flange at each end provided with two sets of holes, a series of bosses on the body portion adapted to be bored and arranged to form stuffing-boxes, and a hand-hole and covering plate, substantially as set forth.
- 50 3. As a new article of manufacture, a fitting for stand-pipes, comprising a body tapering toward the ends and terminating in flanges at each end, a series of bosses on the body adapted to be bored and arranged to form stuffing-boxes, and a hand-hole and cover, substantially as set forth.
- 60 4. As a new article of manufacture, a fitting for stand-pipes, comprising a body tapering toward the ends and terminating in flanges at each end, a series of bosses on the body set at an angle to the axis of the fitting and adapted to be bored and arranged to form stuffing-boxes, and a hand-hole and cover; substantially as set forth.

5. As a new article of manufacture, a fitting for stand-pipes, comprising a body tapering toward the ends and terminating in flanges at each end, a series of bosses projecting through the body at an angle to the axis of the fitting and adapted to be bored and arranged to form stuffing-boxes, and a hand-hole and cover, substantially as set forth.

6. As a new article of manufacture, a fitting for stand-pipes, comprising a body tapering toward the ends and terminating in flanges at each end, two circumferential rows of bosses on the body arranged in vertical alinement and adapted to be bored and arranged to form stuffing-boxes, and a hand-hole and cover, substantially as set forth.

7. As a new article of manufacture, a fitting for stand-pipes, comprising a body tapering toward the ends and terminating in flanges at each end, two circumferential rows of bosses on the body set at an angle to the axis of the fitting and arranged in vertical alinement and adapted to be bored and arranged to form stuffing-boxes, and a hand-hole and cover, substantially as set forth.

8. As a new article of manufacture, a fitting for stand-pipes, comprising a body tapering toward the ends and terminating in stepped flanges at each end, two sets of holes in said flanges, a series of bosses on the body adapted to be bored and arranged to form stuffing-boxes, and a hand-hole and cover, substantially as set forth.

9. As a new article of manufacture, a fitting for stand-pipes, comprising a body tapering toward the ends and terminating in stepped flanges at each end, two sets of holes in said flanges, two circumferential rows of bosses on the body set at an angle to the axis of the fitting and arranged in vertical alinement and adapted to be bored and arranged to form stuffing-boxes, and a hand-hole and cover; substantially as set forth.

10. As a new article of manufacture, a fitting for stand-pipes, comprising a cylindrical body tapering toward the ends and terminating in stepped flanges at each end having two sets of holes, two circumferential rows of bosses projecting through the body at an angle to the axis of the fitting and arranged in vertical alinement and adapted to be bored and arranged to form stuffing-boxes, and a hand-hole and cover, substantially as set forth.

This specification signed and witnessed 120 this 14th day of August, 1917.

WM. F. CONRAN.
